FIG. 3

FIG. 4

FIGURE 1 is a perspective view taken at one end of an expanded metal stamping machine showing my new design.

FIGURE 2 is a perspective view taken at the opposite end of the machine.

FIGURE 3 is a top view of the machine.

FIGURE 4 is a side elevation view of the machine showing the side of the machine which appears at the left of FIGURE 1 and the right of FIGURE 2.

The criss-cross pattern shown in FIGS. 1 and 2 repre-

sents conventional mesh material. It is to be understood that the mesh continues throughout the plain areas shown.

I claim:

The ornamental design for an expanded metal stamping machine, as shown and described.
